WIND MUSICAL INSTRUMENT

Edgar Z. Hall, Durham, N. C.

Application April 14, 1939, Serial No. 267,900

4 Claims. (Cl. 84—375)

This invention relates to wind musical instruments, which I have named a "Lip-A-Fone," and it has for one of its objects the production of a simple and efficient instrument which may be easily played by the lips of a performer and may be used to imitate the notes of various types of birds.

A further object of this invention is the production of a simple and efficient wind musical instrument having a specially constructed and supported reed through the medium of which a performer may whistle or play the melody of any desired tune.

Other objects and advantages of the present invention will appear throughout the following specification and claims.

In the drawing:

- Figure 1 is a side elevational view of the instrument;
 20 Figure 2 is a front elevational view;
 Figure 3 is a bottom plan view;
 Figure 4 is a front elevational view;
 Figure 5 is a vertical sectional view taken on line 5—5 of Figure 4;
 25 Figure 6 is a horizontal sectional view taken on line 6—6 of Figure 5;
 Figure 7 is a vertical sectional view taken on line 7—7 of Figure 5.

By referring to the drawing, it will be seen that 30 10 designates the body of the instrument which tapers from its inner open end 11 toward its outer narrow end 12. The body 10 is provided with a tapering tonal chamber 13. The inner open end 11 constitutes a mouth-piece having an 35 upwardly curved ledge 14. When playing the instrument, the player shall place the instrument to the mouth in a manner to cause the upper back portion of the upper lip to be placed in the groove or V-shaped pockets 24. The instrument should 40 be pushed back against the player's mouth to make a tight fit and to prevent the escape of air, and the center part of the upper lip should rest gently on the reed. When operating the instrument a very small space is allowed between 45 the outer edge of the upper lip just under the nose and the inner portion of the ledge 14. This small air space between the outer portion of the upper lip just under the nose and the inner portion of the ledge 14, as well as the air holes 16 50 and 21 carry the sound into the tonal chamber and out through the funnel or horn 17. A bridge portion 15 extends across the bottom of the tonal chamber 13 near the inner open end 11, as shown in Figure 5, and is inset with respect to the ledge 55 14. The body 10 is provided with an air outlet

16 just beyond or behind the bridge portion 15 and within the tonal chamber 13. The body 10 carries an upwardly flared horn 17 which communicates with the tonal chamber 13.

A relatively thin flexible vibrating reed 18, preferably formed of Kodaloid or other similar material, fits under the bridge portion 15 and extends upwardly and outwardly toward the open end 11, as shown in Figure 5. The upper edge of the reed 18 is curved upwardly toward its center 10 and is spaced from the bridge and free to vibrate. A protector strip of paper or other material 19 is preferably interposed between the bridge 15 and the reed 18. An arc-shaped clamping plate 20 is secured to the bottom of the body 10 below the bridge portion 15 and engages the reed 18 to hold the same firmly clamped between the bridge 15 and the adjustable plate 20. The reed 18 is preferably cemented or otherwise secured to the inner face of the plate 20. This plate 20 is provided with a notch 21 at its rear edge communicating with the air outlet 16 to provide a narrow slit and to facilitate the production of a whistling sound. The clamping plate 20 may be held in place by means of the screws 22. This plate 20 25 is provided with outwardly extending lip-receiving ledge portions 23 near the respective ends of the plate, as shown in Figure 3, to provide substantially V-shaped pockets 24.

The instrument is preferably made of wood, although the same may be made of any suitable or desired material. The horn 17 constitutes a funnel for the escape of the sound and it will be noted that the clamping plate 20 is adjustable by means of the screws 22 and is adapted to hold the curved reed 18 in place, this reed being preferably formed of Kodaloid .003 in thickness. It will be noted that the ledge portions 23, in conjunction with the body, will provide substantially V-shaped pockets or grooves to receive the back 40 portion of the upper lip. The front portion of the upper lip is adapted to rest gently against the vibrating portion of the reed and the lip may be stretched taut or tight by fitting it into the pockets 24 at the corners of the mouth. The lower lip is adapted to rest along the outer edge 25 of the clamping plate 20. It is necessary that the reed 18 be of a very thin and flexible material so as to efficiently vibrate as air is forced between the lip and the reed. Kodaloid has been 50 selected because of the fact that it is moisture-proof and is efficient in operation and reduces the replacement to a minimum. In blowing through the instrument air will also pass out through the openings 16 and 21, and this will assist in creating 55

the desired sound which passes through the funnel or horn 17. When operating the instrument it is preferable to have the ledge portion 14 rest gently against the outer portion of the upper lip 8 just below the nose. The front or flexible portion of the lip, however, should rest gently against the vibrating portion of the reed to obtain the most efficient results. The operator should blow in the same manner employed when producing 10 a whistling sound and should keep the lip gently on the reed. Excessive pressure is not necessary when changing from the lower to the higher notes, and although the pressure is varied it is hardly noticeable. The position of the upper lip 15 may be varied with respect to the reed as it is not necessary that the forward portion of the lip contact exactly the same place on the reed.

By referring particularly to Figure 5, it will be noted that the reed 18 is inserted with respect 20 to the outer ledge portion 14, and that this reed 18 is inclined upwardly when in an opposite direction to the upper face of the inclined upper face of the bridge portion 15. In this way, the reed 18 will be protected and shielded from contact 25 with foreign objects, and because of the fact that the lip of the performer may extend into the relatively wide mouth portion or open end 11 for contact with the reed 18, the reed 18 may be properly vibrated and at the same time properly 30 shielded from injury by foreign objects because of the inset relation of the reed with respect to the outer edge or ledge portion 14.

In playing the instrument, the same principle is used as that employed in whistling a tune, with 35 the exception that only the upper lip is used in conjunction with the reed 18. When placing the reed 18 in position it is preferable to secure the convex side of the reed should it curl up, to the upper face of the plate 20 so that the normal 40 contour of the reed might be followed. When first using the instrument the performer should first make a few sounds to test out the same and with practice any tune may be easily played and the performer may also imitate various types of 45 birds.

It should be understood that certain detail changes in the mechanical construction may be employed without departing from the spirit of the invention, so long as such changes fall within 50 in the scope of the appended claims.

Having described the invention, what I claim is:

1. An instrument of the class described comprising a hollow body constituting a tonal chamber having a relatively wide open lip-receiving portion at one end into which the lip of a performer is adapted to extend, an upwardly extending flexible vibrating reed carried by the body and inset with respect to the outer edge of the 55 lip-receiving portion whereby the outer edge of the lip-receiving portion will shield and protect the reed against injury by foreign objects, the upper edge of the reed being free to vibrate and against which the upper lip of a performer is adapted to rest, the tonal chamber having an 60 outlet, and means for holding the reed within the body portion.

2. An instrument of the class described comprising a hollow body constituting a tonal chamber having a relatively wide open lip-receiving portion at one end into which the lip of a performer is adapted to extend, an upwardly ex- 70

tending flexible vibrating reed carried by the body and inset with respect to the outer edge of the lip-receiving portion whereby the outer edge of the lip-receiving portion will shield and protect the reed against injury by foreign objects, the 5 upper edge of the reed being free to vibrate and against which the upper lip of a performer is adapted to rest, a downwardly extending air duct located at the rear of the reed, an upwardly extending sound-diffusing horn communicating 10 with the hollow body, a detachable clamping plate for removably clamping the reed in position upon the bottom of the body, and outwardly extending lip-receiving ledge portions carried near the 15 respective edges of the clamping plate and located inwardly of the edge of the lip-receiving portion adapted to contact the ends of the lip for stretching the lip taut across the reed as the instrument is firmly pressed against the upper lip of a performer.

3. An instrument of the class described comprising a hollow body constituting a tonal chamber having a relatively wide open lip-receiving portion at one end into which the lip of a performer is adapted to extend, an upwardly extending flexible vibrating reed carried by the body and inset with respect to the outer edge of the lip-receiving portion whereby the outer edge of the lip-receiving portion will shield and protect the reed against injury by foreign objects, the 20 upper edge of the reed being free to vibrate and against which the upper lip of a performer is adapted to rest, and lip-receiving ledge portions carried by the body near the opposite ends of the relatively wide open lip-receiving portion and spaced from the ends of the lip-receiving portion to provide substantially V-shaped pockets for receiving the corners of the mouth of a performer whereby the lip of the performer may be stretched in a taut position in contact with the reed as the 25 instrument is firmly pressed against the upper lip.

4. An instrument of the class described comprising a hollow body constituting a tonal chamber having a relatively wide open lip-receiving portion at one end into which the lip of a performer is adapted to extend, an upwardly extending flexible vibrating reed carried by the body and inset with respect to the outer edge of the lip-receiving portion whereby the outer edge 30 of the lip-receiving portion will shield and protect the reed against injury by foreign objects, the upper edge of the reed being free to vibrate and against which the upper lip of a performer is adapted to rest, and lip-receiving ledge portions carried by the body near the opposite ends of the relatively wide open lip-receiving portion and spaced from the ends of the lip-receiving portion to provide substantially V-shaped pockets for receiving the corners of the mouth of a performer whereby the lip of the performer may be stretched in a taut position in contact with the reed as the instrument is firmly pressed against the upper lip, a bridge portion adapted to 35 clamp the reed in its inset position with respect to the body, an arc-shaped clamping plate secured to the bottom of the body below the bridge portion and engaging the reed for firmly clamping the reed in position, and a protector strip interposed between the bridge portion and the 40 rib.

EDGAR Z. HALL.
